W. R. MILLER,
RIVETING TOOL,
APPLICATION FILED NOV. 23, 1915.

1,216,717.

Patented Feb. 20, 1917.

UNITED STATES PATENT OFFICE.

WALTER R. MILLER, OF BELLVILLE, OHIO.

RIVETING-TOOL.

1,216,717.

Specification of Letters Patent. Patented Feb. 20, 1917.

Application filed November 23, 1915. Serial No. 63,063.

To all whom it may concern:

Be it known that I, WALTER R. MILLER, a citizen of the United States, residing at Bellville, in the county of Richland and 5 State of Ohio, have invented certain new and useful Improvements in Riveting-Tools, of which the following is a specification.

This invention contemplates an improved 10 riveting tool and has as its primary object to provide a device of this character which may be easily manipulated and so constructed that the rivet may be readily forced through the work.

15 The invention has as a further object to provide an improved rivet holder for the plunger of the tool of such character that the rivet will be held in proper alinement relative to the anvil of the tool to enter the 20 work.

And a still further object of the invention is to provide a tool of the above described character wherein the plunger will be normally urged to a position to shift 25 and maintain the rivet holder in operative position relative to the head of the plunger to receive a rivet.

Other and incidental objects will appear as the description proceeds and in the 30 drawings wherein I have illustrated the preferred embodiment of the invention and wherein similar reference characters designate corresponding parts throughout the several views.

35 Figure 1 is a perspective view of my improved riveting tool.

Fig. 2 is a fragmentary elevation partly in section and particularly showing the mounting of the plunger of the tool, and

40 Fig. 3 is a fragmentary perspective view showing the plunger and rivet holder detached.

In carrying out my invention, I employ 45 a channeled stock 10 which is offset intermediate its ends and is then extended to provide an operating lever or handle 11. The stock is formed with spaced sides 12 which are connected at longitudinally spaced points adjacent the upper end of the stock 50 by transversely extending parallel webs 13 and 14 respectively. Extending laterally from the upper end of the stock is a substantially U-shaped neck or yoke 15, having its free end terminating in alinement with the webs 13 and 14 and provided with a screw threaded bore adjustably receiving an

anvil or set screw 16 presented toward the said webs. The set screw 16 is provided with a flat inner end and is formed axially with a longitudinally extending spur or nib 60 adapted to engage between the prongs of a rivet for upsetting the rivet.

Formed on the sides 12 of the stock adjacent the upper extremity thereof are laterally extending spaced ears 17 which pivotally receive an operating lever or handle 18 adapted to coöperate with the handle 11 and supported upon the said ears by a suitable pivot pin extending therebetween. The handle 18, at its inner end is provided with 70 a laterally extending head or arm 19 extending freely between the sides 12 of the stock beneath the web 14 and is also formed with a longitudinally extending stop lug 20 at its outer edge adapted to engage the 75 web 14 for limiting the handle 18 in its outward swinging movement relative to the handle 11. Preferably, the arm 19 is provided with a flat upper face.

The webs 13 and 14 are provided with 80 registering openings which freely receive a plunger 21 arranged in alinement with the anvil 16 and shiftable upon the said webs either toward or away from the said anvil to coöperate therewith. At its outer 85 end, the plunger 21 is formed with a cylindrical head 22 having a flat upper face presented toward the anvil. Freely surrounding the head 22 of the plunger is a substantially cylindrical rivet or fastening holder 90

23 shown in detail in Fig. 3 of the drawings. This rivet holder is preferably formed of suitable resilient sheet metal and the wall thereof is slit longitudinally at a plurality of circumferentially spaced points to provide coacting tongues or fingers 24. At its inner end, the rivet holder 23 is provided with a radial flange 25 which connects the tongues 24 at their inner extremities and freely surrounds the plunger 21, the said 100 flange being adapted to engage the shoulder formed by the inner end of the head 22 of the plunger to limit the rivet holder in its outward shifting movement upon the head. Adjacent its outer extremity, the wall of the rivet holder is provided with a bead which forms an annular shoulder 26 arranged, when the flange 25 is seated against the inner end of the head 22, in spaced relation above the upper flat face of the said 105 head to project inwardly thereover, as more particularly shown in Fig. 2. From the

shoulder 26 the wall of the rivet holder is then flared outwardly toward its free edge to provide a cup-shaped or frusto-conical terminal 27 presented toward the inner end 5 of the anvil 16, each of the tongues 24 of the rivet holder being thus provided at its outer end with an inclined inner face sloping toward the upper flat face of the head 22 of the plunger.

- 10 Extending transversely through the plunger 21 adjacent the inner extremity thereof is a pin 28 and interposed between the said pin and the web 13 of the stock is a helical spring 29 which surrounds the 15 plunger and is adapted to urge the plunger to normal position with the flange 25 of the rivet holder seated against the outer face of the said web, this spring normally urging the plunger away from the anvil 16.
- 20 The plunger 21 at its inner extremity projects through the web 14 of the stock to be engaged by the flat upper face of the arm 19 of the handle 18 so that when the said handle is swung toward the handle 11 of the 25 stock, the arm 19 will urge the plunger toward the anvil against the action of the spring 29.

In operating the tool, the handle 18 is first swung outwardly away from the handle 30 11 to such position that the spring 29 will shift the plunger to engage the flange 25 of the rivet holder with the upper face of the web 13 of the stock. The rivet holder 23 will then be moved to a position with the 35 shoulder 26 thereof spaced above the upper flat face of the head 22 of the plunger. The head of a rivet is then placed within the cup-shaped terminal 27 of the rivet holder when slight downward pressure upon the 40 rivet will serve to spring the tongues 24 of the rivet holder outwardly so that the head of the rivet will move to a position seated against the flat upper face of the head 22 of the plunger with the shoulder 26 of the 45 rivet holder engaged over the head of the rivet and with the prongs of the rivet directed upwardly toward the anvil 16 in position to pierce the work. The work is, of course, inserted between the rivet and the 50 anvil and the handle 18 may then be operated to properly actuate the plunger and readily force the rivet through the work to engage the anvil which will then act to overturn the rivet, the anvil being adjustable 55 upon the neck 15 to accommodate work of various thicknesses.

Particular attention is now directed to the fact that by providing the rivet holder 23 with a cup-shaped terminal, the head of the rivet upon being engaged with the inclined inner faces of the tongues 24 of the rivet holder may be easily seated upon the upper face of the head 22 of the plunger and when engaged with the shoulder 26 of the rivet 65 holder, the rivet will be held firmly with its

prongs properly positioned to pierce the work, it being noted that the tongues 24 will yieldably engage with the periphery of the head of the rivet throughout its entire circumference so that the rivet cannot shift laterally upon the head of the plunger. When the handle 18 is operated to move the plunger 21 upwardly and engage the rivet with the work, the upper edge of the rivet holder will contact with the work so that 75 subsequent upward movement of the plunger will act to disengage the rivet holder from the rivet when the rivet holder will drop upon the plunger to seat against the web 13 of the stock. However, it will be 80 noted that before the rivet holder is thus disengaged from the rivet, the prongs of the rivet will be held embedded in the work so that the presence of the rivet holder about the head of the rivet will not be further required to properly direct the rivet into engagement with the work. After the rivet has been properly overturned against the anvil 16 and the handle 18 is again swung outwardly from the handle 11 of the stock, 85 the spring 29 will then shift the plunger away from the anvil and will act to move the head 22 of the plunger into the rivet holder and over the shoulder 26 thereof to 90 normal position within the said holder, the holder being seated against the web 13 and the spring 19 urging the head of the plunger toward the said web. In this position of the rivet holder and plunger, another rivet may then be inserted within the rivet holder 100 to engage the head of the plunger in the manner above described. It will therefore be seen that each time the plunger 21 is moved to engage a rivet with the work, the rivet holder 23 will, at the proper time, be 105 automatically disengaged from the rivet and that when the handle 18 is released, the plunger will then again be moved to automatically shift the rivet holder to operative 110 position relative to the head of the plunger to receive another rivet.

Having thus described my invention, what I claim and desire to secure by Letters Patent is:

1. A device of the character described including a stock provided with an anvil, a plunger shiftable upon the stock to coöperate with the anvil, an operating lever for the plunger, and a holder carried by the plunger for movement longitudinally thereon, the said holder being provided with a cylindrical wall split to form a plurality of yieldable gripping tongues adapted to engage a fastening. 115

2. A device of the character described including a stock provided with an anvil, a plunger shiftable upon the stock to coöperate with the anvil, an operating lever for the plunger, and a rivet holder normally surrounding one end of the plunger to co- 120

130

5 operate therewith and provided with a frusto-conical outer end terminating at its inner extremity in a shoulder projecting inwardly over the said end of the plunger, the frusto-conical outer end of the rivet holder being adapted to direct the head of a rivet toward the said end of the plunger to engage beneath the said shoulder.

10 3. A device of the character described including a stock provided with sides, a web connecting the said sides, an anvil carried by the stock, a plunger shiftable upon the stock to coöperate with the anvil, an operating lever for the plunger swingingly mounted upon the stock, and a longitudinally extending stop lug carried by the inner extremity of said lever and adapted to engage said web for limiting the lever in its outward swinging movement away from the 20 stock with the plunger disposed in spaced relation to the anvil.

15 4. A device of the character described including a stock provided with an anvil, a plunger shiftable upon the stock to coöperate with the anvil, means for shifting the plunger, and a fastening holder carried by the plunger and provided with a laterally deflected portion at its outer extremity adapted to direct a fastening to seat against 30 the plunger.

25 5. A device of the character described including a stock provided with an anvil, a plunger shiftable upon the stock to coöperate with the anvil, means for shifting the plunger, and a fastening holder carried by the plunger and provided with a cup shaped outer extremity adapted to direct a fastening to seat against the plunger.

30 6. A device of the character described including a stock provided with an anvil, a plunger shiftable upon the stock to coöperate with the anvil, means for shifting the plunger, and a fastening holder carried by the plunger and provided with a shoulder

45 with the wall of the holder at its outer extremity sloping toward said shoulder for directing a fastener to engage beneath the shoulder with the fastener resting against the plunger.

50 7. A device of the character described including a stock provided with an anvil, a plunger shiftable upon the stock to coöperate with the anvil, means for shifting the plunger, and a fastening holder carried by the plunger and provided with a shoulder 55 adapted to engage over the head of a fastening seating upon the plunger with the holder acting to hold the fastening tightly against the plunger.

55 8. A device of the character described including a stock provided with an anvil, a plunger shiftable upon the stock to coöperate with the anvil, means for shifting the plunger, and a fastening holder carried by the plunger and provided with a shoulder 60 normally adapted to support the holder in operative position upon the plunger and adapted to engage the head of a fastening with the said fastening seating against the 65 plunger.

70 9. A device of the character described including a stock provided with an anvil, and a plunger shiftable upon the stock to coöperate with the anvil and provided with a shoulder, means for shifting said plunger, 75 and a fastening holder carried by the plunger and provided with a flange adapted to engage said shoulder for limiting the holder in its movement to active position upon the plunger and having a shoulder 80 formed thereon adapted to engage the plunger for supporting the holder in active position with the shoulder of the holder adapted to engage the head of a fastening seating against the plunger.

85 In testimony whereof, I affix my signature.
